TIME SYSTEM

Richard L. Lorenz, Chicago, Ill., assignor to General Time Instruments Corporation, New York, N. Y., a corporation of Delaware

Application September 16, 1942, Serial No. 458,601

7 Claims. (Cl. 58—24)

This invention relates in general to time systems and more particularly to a corrective or synchronizing time system in which the individual secondary units are periodically corrected to bring them into synchronism with the master clock or control unit. The main object of the invention is to provide a system of this type in which the current for the controlling impulses for the timing magnets and the operating current for the printing magnets or other means in the secondary devices are always of the same characteristics, thereby permitting all circuits to be run from the central control point to the secondary apparatus in a single system of conduit.

In known systems which include recorders or time stamps having electrical printing means, the current for operating the printing means is usually of higher voltage and often differs in other characteristics from the current used for the timing and correcting impulses. In such cases the usual practice is to obtain the operating current from a power outlet near the device, or to run a separate system of conduit for the power leads if it is desired to supply this operating current from the control point. According to the present invention, only one system of conduit is required for all control circuits between the master and secondary apparatus.

According to another feature of the invention, no electrical contacts are required in the timing and synchronizing control circuits of the secondary apparatus, thereby eliminating one of the chief sources of trouble in corrective time systems.

Other objects and features of the invention will be apparent from a perusal of the following specification when read in connection with the accompanying drawing, comprising one figure only, which is a diagrammatic representation of a corrective time system incorporating the present invention.

In the drawing, M shows diagrammatically parts of the master or control clock with the various control cams and contacts, S—1 illustrates a secondary device which is slow with respect to the master clock, and S—2 illustrates a secondary device which has been stopped during the synchronizing period.

Referring in detail to the drawing, the master clock M is of the usual type and has therefore been shown only diagrammatically, omitting all standard parts not necessary for an understanding of this invention.

The master clock includes the usual verge mechanism 1 and the escape wheel 2, the latter being mounted on a shaft which revolves once per minute. Also mounted on the shaft with the escape wheel is the cam 3 which controls the contacts 6, whereby these contacts are momentarily closed once each minute for a period of one or two seconds.

The verge 1 is provided with a pair of oppositely extending contact operating levers which control the contacts 4 and 5. Thus the contacts 4 and 5 are alternately closed during successive oscillations of verge 1.

The master clock is also provided with two cams, 7 and 8, mounted on the minute shaft. The cam 7 is provided with a notch in its periphery and controls the contact carrying lever 9 which mounts the contact spring 10. Cam 8 is similarly provided with a notch in its periphery and controls the contact lever 45. These two cams co-operate in controlling the opening and closing of the contacts 11 and 12 in a manner 15 to be described later.

13 and 14 indicate lines extending to a source of 110 volt alternating current.

Two secondary devices S—1 and S—2 have been shown in the drawing. These may be secondary clocks, recorders or time stamps and only sufficient parts have been shown to enable one to obtain a clear understanding of the operation. The devices illustrated in the drawing are time stamps or recorders of the so-called automatic type in which the printing operation is electrically effected by the insertion of a card or paper into the device.

Referring to the illustration of S—1, the device includes a printing or hammer operating magnet 23, the circuit of which is controlled by the card or paper operated contacts 24. The device includes the usual timing magnet 19 which responds to impulses received over the control circuit from the master clock. The magnet 19 is 30 provided with an armature lever 20 which carries the operating pawl 35 at its upper end. This pawl engages the teeth of the ratchet wheel 40 which is mounted on the minute shaft of the secondary device. The ratchet wheel 40 is 35 provided with 60 teeth and therefore makes one revolution per hour in response to the minute impulses received from the master clock.

A retaining pawl 34 is provided in order to prevent retrograde movement of the ratchet wheel. 40 Spring 36 interconnects the two pawls to maintain them in engagement with the ratchet wheel 40. A stop 22 is provided to limit the movement of armature lever 20 and the armature lever is held against this stop by the operating spring 21. 45 Thus each time the magnet 19 is energized, the armature lever moves against the pole pieces of the magnet and the pawl 35 engages the succeeding tooth on the ratchet wheel 40. When the magnet de-energizes, the operating spring 21 restores the armature lever against stop 22 and during this movement the ratchet wheel 40 is advanced $\frac{1}{60}$ of a revolution.

Also mounted on the minute shaft is a disc 37 which has a notch 38 in its periphery. This 50 notch 38 is adapted to be engaged by a projection

39 formed at the upper end of one arm of the bell crank lever 32. This bell crank lever is pivotally mounted on armature lever 20 and the projection 39 is held against the periphery of disc 37 by spring 33. A stop 46 is provided on the armature lever to limit the counter clock-wise movement of the crank 32. Also pivotally mounted on an extension of the armature lever 20 is a lever 29 having a tail which is normally held against the stop 31 by means of spring 30. The end of lever 29 rests against the plunger 27 of a solenoid type magnet 26.

The system is arranged to provide hourly correction of the secondary devices. S-1 shows the secondary apparatus prior to the synchronizing or correction period. As time magnet 19 is energized the armature lever 20 is attracted and the projection 39 is held tightly against the periphery of disc 37 by spring 33. Bell crank lever 32 thereby revolves in a clock-wise direction on the armature lever. Similarly the upper end of lever 29 rests against plunger 27 and when armature lever 20 is operated, lever 29 revolves clock-wise on its pivot stretching the spring 30. When magnet 19 is de-energized, the parts return to the position shown in the drawing and the ratchet wheel 40 and disc 37 are advanced the space of one tooth.

When the secondary devices reach the synchronizing position and magnet 19 is energized, the projection 39 enters slot 38, thereby permitting the plunger 27 to drop behind projection 39 and lock the bell crank lever 32 in this position. This also locks the armature lever 20 in its attracted position even after the magnet 19 is de-energized since the lower arm of bell crank lever 32 rests against stop 46.

The downward motion of plunger 27 is limited by the pin 28 projecting from the side of this plunger which pin engages the top of lever 29. After the synchronizing period, the solenoid magnet 26 is energized simultaneously with the timing magnet 19. The plunger 27 is drawn upwardly releasing lever 29 which turns counter-clockwise on its pivot until the tail thereof engages stop 31. This places the end of the lever beneath the plunger 27 and maintains the plunger in position when the magnet 26 is de-energized.

When magnet 19 is de-energized the armature lever 20 returns to unoperated position and during this return movement, lever 29 is moved from beneath plunger 27 and is replaced by the upwardly extending arm of bell crank lever 32. Plunger 27 drops until it rests on the upper end of the bell crank lever. The parts have now been returned to the position shown for S-1.

S-2 diagrammatically shows a secondary device which has been locked in inoperative position during the synchronizing period. The armature lever 20 is held in operated position, the projection 39 is locked in the slot 38 by plunger 27 which has dropped so that the pin 28 rests on the end of lever 29.

Half wave rectifier units 25 are provided in the circuits of the timing magnets and the solenoid magnets in order to reduce the current consumption of the secondary devices. The printing magnets 23 are operated directly by the alternating current over control conductors 17 and 18.

Having described the construction of the master clock and secondary devices, the method of operation of the system will now be explained.

Contacts 6 are closed once each minute by cam 3, thereby completing a circuit from the power

line 13, contact 6, conductor 18 of the control circuit extending to the secondary device, conductor 41, magnet 19, rectifier unit 25, conductor 43, line 16 to the power line 14. This completes the circuit to the timing magnet 19 which momentarily operates and advances the ratchet wheel 40 $\frac{1}{60}$ of a revolution upon de-energization of the magnet, as has been explained above.

The contacts 11 and 12 are normally open when the contact carrying levers 9 and 45 are riding upon the peripheries of cams 7 and 8. At approximately 59 minutes and 10 seconds after the hour the contact carrying lever 45 drops into the notch of cam 8, thereby closing contacts 12. This completes a circuit from power line 13 through contacts 12 and the verge controlled contacts 4 and 5 which are alternately operated about every two seconds, line conductor 18, through the secondary timing magnets such as 19, and back to the other side of the power source 14 over line conductor 16. The fast impulses transmitted over this circuit rapidly advance any secondary device which may be slow with respect to the master clock and has not yet reached its 59th minute position. When the secondary device reaches its 59th minute position, the slot 38 is opposite projection 39 and upon the succeeding energization of magnet 19 the projection enters the slot and the armature lever is locked in energized position by means of plunger 27 as has been previously described. This position of a secondary device is shown in the representation of S-2. Each succeeding fast impulse has no effect upon the locked secondary device. Thus it is seen that any device which is fast with respect to the master clock will be locked in position 59 as soon as it reaches such position. Any device which is slow will be rapidly advanced by the fast impulses which are transmitted from the master clock between the 59th and 60th minute, and will be locked in the 59th minute position, and thereafter will be inoperative by the remainder of the fast impulses.

Shortly after 59 minutes and 10 seconds after the hour, the contact carrying lever 9 drops in the notch in cam 7 but this does not lower the contact lever 10 sufficiently to close contacts 11.

When the master clock reaches a position corresponding to 59 minutes and 50 seconds after the hour, the contact carrying lever 45 is raised by cam 8, opening contacts 12 to stop the transmission of fast impulses to the secondary devices, and closing contacts 11. When the master clock reaches the even hour position, contacts 6 are again closed by cam 3, thereby completing a circuit to the timing magnets of the secondary devices as previously described and also completing a circuit through contacts 6, contacts 11, line conductor 15, solenoid magnets 26, rectifier units 25, conductors 43, and back to the other side of the power source over line conductor 16. The solenoid magnets in the secondary devices are thus energized simultaneously with the timing magnets, raising plungers 27 and permitting levers 29 to revolve counter-clockwise to bring the ends thereof underneath these plungers.

At the termination of the 60th minute impulse, the timing magnets and the solenoid magnets are de-energized restoring the secondary apparatus to the normal condition as illustrated in S-1.

From the foregoing explanation, it will be apparent that the system provides for correction of the secondary apparatus once each hour or other desired period during which correction all slow secondaries are advanced into synchronization with the master clock and all fast secondaries

are locked in a pre-determined position until the master clock reaches such pre-determined position. All the secondary devices are then started off in synchronism by the master clock. All of this control is accomplished by impulses all of which have the same characteristics. This eliminates the undesirable features of prior systems in which it was necessary to provide impulses of reversed polarity, impulses of two different voltages, or both alternating and direct current impulses.

It will also be noted that the operating current for the printing magnets in the secondary devices is obtained from the center control point and that this current is of the same characteristics as the control impulses. This permits all of the control conductors from the master clock to the secondaries to be run in the same conduit.

Prior systems which used one type of current for controlling impulses and another high voltage current for the operating magnets required the running of two systems of conduit or obtaining the current supply for the printing magnets locally for each device and thereby losing the desirable feature of having all of the current supply originate from the control station.

Although only one particular embodiment of the invention has been disclosed and described herein, it will be apparent to those skilled in the art that many modifications and changes in the mechanism may be made without departing from the spirit of the invention as defined in the following claims.

Having described the invention, what is claimed as new and is desired to have protected by Letters Patent is:

1. In a secondary apparatus for use in a corrective time system, an impulse magnet and an armature therefor for effecting all advancing movements of said apparatus, means automatically effective when said apparatus reaches a predetermined chronological position for mechanically blocking said armature in its attracted position to prevent effective movement thereof by said magnet, a second magnet for removing said blocking means from blocking position, and means for holding said blocking means in non-blocking position until said apparatus has advanced from said predetermined chronological position.

2. In a secondary apparatus for a corrective time system, an impulse magnet controlled by impulses received over a control circuit, an armature for said magnet for effecting all advancing movements of said apparatus, a synchronizing disc rotated by said magnet and having a notch in its periphery, a bell crank lever pivotally mounted on said armature and having one arm engaging the periphery of said disc and adapted to engage said notch in a pre-determined chronological position of said apparatus, mechanical blocking means normally held in ineffective position by said arm and released when said arm enters said notch to hold same therein and to lock said armature in energized position, and electrical means for moving said blocking means to non-blocking position.

3. In a secondary apparatus for a corrective time system, an impulse magnet controlled by impulses received over a control circuit, an armature for said magnet for effecting advancing movement of said apparatus, a bell crank lever

pivotedly mounted on said armature for limited movement relative thereto, means normally engaging the end of one arm of said lever to hold same against movement whereby said lever oscillates about its pivot during movements of said armature, said means ineffective in a pre-determined position of said apparatus, mechanical blocking means normally held in inoperative position by said arm and released thereby when said apparatus reaches said pre-determined position to block said armature in its energized position, and means controlled over said control circuit for removing said blocking means from blocking position.

15 4. In a secondary apparatus for use in a corrective time system, an impulse magnet having an armature and pawl for effecting advance of said apparatus in response to impulses received over a control circuit, mechanical blocking means

20 for blocking said armature in energized position to prevent advance of said apparatus by received impulses, holding means for maintaining said blocking means in non-blocking position, means controlled by the chronological position of said apparatus for removing said holding means whereby said blocking means becomes effective to block said armature, and means controlled over said control circuit for restoring said blocking means to non-blocking position.

25 5. In a secondary apparatus for use in a corrective time system, electrically operated advancing means for said apparatus, mechanical blocking means for blocking advance of said apparatus, holding means for normally holding said

30 blocking means in non-blocking position, means controlled in accordance with the chronological position of said apparatus for releasing said holding means whereby said blocking means moves to blocking position, electrically operated means for restoring said blocking means to non-blocking position, and auxiliary holding means for holding said blocking means in non-blocking position until said normal holding means is restored to holding position.

35 6. In a secondary apparatus for use in a corrective time system, electrically operated advancing means for said apparatus, mechanical blocking means for blocking advance of said apparatus, holding means for maintaining said blocking

40 means in non-blocking position, and means for removing said holding means to permit said blocking means to assume blocking position, said means being operative only when said apparatus is at rest in a particular predetermined chronological position.

45 7. In a secondary apparatus for use in a corrective time system, electrically operated advancing means for said apparatus, mechanical blocking means for blocking said advancing means, holding means for maintaining said blocking

50 means in non-blocking position, means effective in a predetermined chronological position of said apparatus for removing said holding means to permit said blocking means to assume blocking position, means for restoring said blocking means to non-blocking position, and means for holding said blocking means in non-blocking position until said first holding means is returned to holding position upon advance of said apparatus from said predetermined chronological position.

RICHARD L. LORENZ.
